UNITED STATES PATENT OFFICE.

GEORGE EASTMAN AND WILLIAM H. WALKER, OF ROCHESTER, NEW YORK,
ASSIGNORS TO THE EASTMAN DRY PLATE AND FILM COMPANY, OF
SAME PLACE.

APPARATUS FOR MANUFACTURING SENSITIVE PHOTOGRAPHIC FILMS.

SPECIFICATION forming part of Letters Patent No. 358,848, dated March 8, 1887.

Application filed October 25, 1884. Serial No. 146,449. (No model.)

To all whom it may concern:

Be it known that we, GEORGE EASTMAN and WILLIAM H. WALKER, citizens of the United States, residing at Rochester, New York, have 5 invented certain Improvements in Apparatus for Manufacturing Sensitive Photographic Films, of which the following is a specification, reference being had to the accompanying drawings.

10 Our present invention relates to improvements in the apparatus for manufacturing our improved sensitive flexible photographic films, such as described in Letters Patent Nos. 306,594 and 306,470, issued October 14, 1884, 15 which improvements are fully described in the following specification, and the novel features thereof specified in the annexed claims.

Our improved apparatus for manufacturing sensitive photographic films is represented in 20 the accompanying drawings, in which—

Figure 1 is a side elevation. Fig. 2 is a plan view. Fig. 3 represents a portion of the apparatus, showing the coating devices on an enlarged scale. Fig. 4 is a side elevation of the 25 mechanism which operates the rollers which support the coated films while drying. Fig. 5 is a plan view of the same. Figs. 6 and 7 represent end and plan views of the coating-roll, respectively. Fig. 8 is a plan view of the 30 coating-roll, showing the scraper. Fig. 9 is a sectional view showing the mechanism for feeding the rollers onto the elevating-chains.

Our improved apparatus consists, essentially, of a suitable frame or frame-work, A, 35 which supports the roll of uncoated paper B and the coating apparatus, and of a suitable mechanism, (shown at the left hand in Fig. 1,) in which the coated paper is automatically hung up to dry in pendent loops.

40 The coating apparatus is illustrated on an enlarged scale in Fig. 3, in which B is a roll of uncoated paper, the course traversed by which as it is unwound, coated, and passed through the machine being represented by the line B'. The roll of paper is provided with 45 suitable journals projecting from each end and arranged to revolve in bearings in the up-rights D, attached to a bar, C, of the supporting-frame. The trough for containing the

substratum or the emulsion which is to be applied to the paper is represented at E.

F F' are a pair of guide-rollers between which the paper passes.

G is another guide-roll, and H the coating-roll, the lower side of which runs in the fluid 55 in the trough E.

I, J, K, L, and M are other rollers, about which the paper passes on its way to the looping and drying part of the apparatus.

Power is applied to the machine by means 60 of the driving-shaft N, Figs. 1 and 2, which receives motion from a belt running over the pulley O, and distributes it by means of the belts a b c.

While it is advantageous to apply power to 65 all of the rolls, we have found in practice that it is possible to feed the paper by driving the roll M in connection with one of the intermediate rolls, preferably the roll I, next the trough containing the emulsion.

The rolls F F', if used, are supported in any 70 suitable manner from the main frame, so that the paper passes through them as it leaves the roll B, and is to a certain extent guided and caused to unroll smoothly by them. The roller 75 G is sustained in place by the frame P, pivoted at f to the standards D, so that it can be swung upward to afford access to the coating-roll, as indicated by the dotted lines in Fig. 3.

The roller G serves to wrap the paper closely 80 about the coating-roll H on the side on which it runs onto the latter. The coating-roll revolves in suitable journals attached to the trough E in such position that the lower portion of the roll, with the paper wound about 85 it, is immersed in the emulsion or other liquid. The roll is made longer than the width of the web of paper which it is designed to coat in the machine, and in order to prevent the liquid from covering the roll so as to smear the back 90 of the paper or film we employ the scrapers e, Figs. 6 and 8, at each end of the roll, which are so shaped as to throw the liquid outward beyond the edges of the paper. The lower surface of the scraper bears on the upper side 95 of the roll, and is made of a shape to correspond with the curvature of the roll. The outer side of the scraper is inclined to the axis

of the roll, as shown in Fig. 8, so that the operation of the scraper is, as the roll revolves, to clean the upper surface of the roller at the edge of the paper and cause the liquid to flow 5 outward along the roll, thereby preventing any of the liquid from getting onto the back or uncoated side of the paper film which runs in contact with the roll. The scrapers are pressed downward against the upper surface 10 of the roll by a spring, *g*, Fig. 6. The scrapers should be arranged so that they can be easily removed, to afford access to the coating-roll; and in practice we have found that a convenient way of accomplishing this result is to 15 support them by means of a rod or rods, *d*, passing through a block, *h*, fastened to a rod, *i*, extending across the frame *G*. The blocks are secured to the rod by means of a set-screw, which permits of the removal of the scraper 20 from contact with the coating-roll.

The web of paper, when the machine is in operation, passes about the lower side of the coating-roller *H*, being coated on its outer or lower surface as it passes around the roll. 25 The coating-roll revolves from the friction of the paper. Sufficient tension may be maintained on the paper web by any suitable friction device acting on the paper-roll *B* or the rolls *F F'*. The web of paper passes upward 30 from the coating-roll about the roller *I*, which revolves in suitable supports or bearings on the frame-work, and then horizontally about the roller *J*, and then descends, passing about one or more rollers, *K L*, below the 35 coating devices, before it passes upward to *M*, from which it is delivered to the looping and drying apparatus. The web of coated paper may be caused to pass more than once about the coating devices by means of a suitably-40 arranged set of rollers. The object of passing the coated paper around the coating devices is to allow sufficient time to elapse before the paper is delivered to the looping apparatus, to enable the coating to set or stiffen. The passing 45 of the paper around the coating apparatus also increases the friction of the feeding-rolls *I* and *M* on the paper and enables them to draw it smoothly and easily. By running the paper upward and downward, also, we have observed 50 that we secure greater uniformity in the coating.

The coating-roller *H* is preferably brass, with suitable bearings to support it on the centers on the trough *E*. We have, however, 55 used rubber and wooden rollers. It is unnecessary to remark that the trough and all metallic parts which come in contact with the sensitive emulsion should be formed of or plated with a metal—such as silver—which is 60 not acted on chemically by the emulsion.

The apparatus for hanging up the paper in loops to dry consists, essentially, of two parallel inclined elevating belts or chains, *S S'*, and two carrying or conveying chains, *T T'*, 65 provided with suitable mechanical attachments by which a series of rollers, *U U*, upon

which the loops of coated paper are suspended, are operated. The whole apparatus is supported by a suitable frame-work, which, for convenience of illustration, has been omitted 70 in the drawings. Motion is transmitted to the elevating-chains *S S'* by means of sprocket-wheels *j j* on a shaft supported in bearings *k k* and receiving power from the main driving-shaft *N* by means of the belt *a* and suitable 75 pulleys. Suitable inclined ways or guides, *V*, are arranged to support the chains, which travel upward along the upper sides of these inclined ways, as indicated by the arrows in the drawings. At their upper ends the chains 80 run over the sprocket-wheels *Y Y*, *Y' Y'*, which revolve on suitable studs, *l l*, Fig. 4, projecting inward from the supporting-frame, but leaving the space between the wheels *Y Y*, *Y' Y'* open for the passage of the loops of paper 85 *B* between them. The chains *S S'* are provided with one or more projecting studs, *m m*, which carry the rollers *U* up the inclined guides *V*. The rollers are fed onto the chain automatically by the device represented in 90 Fig. 10, in which *j* represents one of the sprocket-wheels, and *n* an inclined trough or guide for the ends of the rollers, arranged just outside of the chain and wheel. The rollers are placed in the inclined guides *n*, which are 95 open at their upper ends for this purpose, and as fast as the lowest roller is carried upward by the lugs *m* on the chain *S S'* the remainder of the rollers drop downward in the guides, so as to bring the lowest roller in position to 100 be elevated. A notch or opening is made at *o*, Fig. 10, in the guides, to permit of the removal of the lowest roller by the lugs on the chains. As the rollers are elevated up the inclined guides *V V*, they come in contact with 105 the paper hanging in a curve between the roller *M* at the top of the frame *A* and the first roller *U* on the chains *T T'* and elevate it in a loop, as shown at *B'' B'''*, Fig. 1. The chains *T T'* are provided with a series of projecting lugs, *p p*, Figs. 4 and 5, arranged at 110 distances from each other equal to the width of the pendent loops of paper *B*. As the rollers arrive in succession at the upper ends of the chains *S S'*, they are disengaged therefrom 115 and placed on the chains *T T'* by the mechanism shown in Figs. 4 and 5. The rollers *U* are made longer than the width of the chains, 120 so that their ends project over the chains *T T'*, which are placed just outside of the chains *S S'*. The roller *U*, Fig. 4, arriving above the sprockets *Y Y*, comes in contact with the lugs *p* on the chains *T T'*, and causes the latter to move onward for a distance equal to the width 125 of the loops, the chains carrying all the pendent loops *B* along at the same time. The lug *m* is disengaged from the roller *U* as it moves onward by the inclination given to the chains *S S'*, the sprockets *Y' Y'* being placed lower than the sprockets *Y Y*, so that as the chains 130 *S S'* move on in an inclined direction, while the rollers travel on horizontally or at a less

inclination on the chains T T', the lugs m are gradually disengaged from their contact with the rollers, as represented at m', Fig. 4, so that the motion of the chains T T' is arrested 5 when the roller arrives at U', Fig. 4, and the paper hangs in a loop between rollers U' and M, ready for the next roller in the series to be elevated by the chains S S', forming another loop of paper, as already described.

10 Guides W, Fig. 4, (indicated by dotted lines in Fig. 5,) are placed above the outer ends of the rollers, to prevent any tendency in the rollers to be forced upward by the lugs m and p. Between the sprockets Y Y' the chains S S' 15 are supported by the guide Z, Fig. 4, which is fastened to the plates or frame-work q q, which support this part of the apparatus. A spring, r, is used to prevent the rollers from moving backward accidentally or by the weight of loop 20 between U' and M, being arranged to yield into a recess in the plate q when the ends of the rollers pass by it. The chains T T' are preferably inclined, so that their upper sides run downward slightly, thereby insuring that the 25 rollers shall remain in contact with the lugs or studs p on the chains. The chains T T' may be supported in place by suitable ways or guides.

It is unnecessary to remark that the apparatus 30 should be used in coating sensitive emulsion in a suitable non-actinic light. Provision should also be made to maintain the liquid in the trough E at a suitable temperature during the coating operation by making the trough 35 with an internal partition, into which steam or hot water are admitted.

We prefer to make the trough of such a form that the coating-roller reaches almost to the bottom of it, as indicated by the dotted lines 40 in Fig. 3.

The method of coating paper with sensitized gelatino-argentie emulsion, as described, is not claimed herein, but is reserved for a separate application prepared and about to be filed 45 by us.

We are aware that it is not new to coat a web of paper by causing the same to move in contact with a roll partially submerged in the coating material, the roll operating to transfer the material to the web, as illustrated in the patents to Hale, No. 87,407, and Ferguson, No. 201,340; and we are also aware of the fact that machines for coating fabrics have been devised 50 wherein the coating material is applied to the web and spread evenly thereon by the action of scrapers, and the web is carried by rollers and deposited on a drying-frame, as described in patents to Allen, No. 162,332, and Chaffee, No. 44,281; hence we do not claim said matter- 55 ters, our invention involving the use of a partially-submerged roller, by which the paper is carried into the emulsion to be coated on one side only, a series of carrying or conducting rolls and a hang-up frame of any approved construction being located at such distance from the coating-roll that the gelatino-argentie emul-

sion may have time to set before the web is deposited on the drying-frame.

As will be readily understood, the coating of endless strips or webs of paper with a thin uniform coating of sensitized emulsion such as is desirable for photographic purposes is attended with much difficulty; and in order to properly distribute the coating and maintain it of a uniform and even thickness while setting and drying, the paper must be held under a certain degree of tension sufficient to feed the paper through the machine and hold it flat, and at the same time not great enough to draw the paper unevenly, so as to form wrinkles in the surface.

The ordinary feeding devices, such as are usually employed for drawing webs of paper or fabrics through coating machinery, cannot be applied in machines of the kind herein described, for the reason, among others, that the paper as it emerges from the bath is wet and limp, its coating of sensitized gelatine is in a semi-fluid state, and will not bear handling; hence the feed devices, which must be positive and uniform in action, must be so arranged and applied as not to bear upon or in any way make contact with the coated face of the paper. It is for this reason that the paper in our machine is carried around rollers so disposed as to retain the coated web in motion for a length of time sufficient to permit the hardening of the coating before the web is delivered to the drying mechanism, and we utilize two or more of the rolls over which the coated 95 web is passed as feeding devices by applying power to rotate said rolls, the frictional contact with the under surface of the paper being found just sufficient to properly carry the paper without unduly straining or wrinkling it.

It is to be borne in mind that the paper web as it emerges is impregnated with moisture, and is in condition to receive the impression of any irregular or pointed object pressed against it from either face; hence nothing but smooth plain-faced rolls can be used as feeders or sustainers. The necessities of the case demand, therefore, a feeding mechanism which, when applied to the back of the coated paper, shall be competent to operate thereon by the frictional contact of a smooth and even surface to draw the paper evenly and regularly through the machine and deposit it in a loose condition upon the drying-frame. All these necessary conditions are fulfilled in the machine herein described. The rollers M and I being driven—the one, I, applied immediately above the coating-bath, and the other, M, at the delivery end of the machine—the roll I operates upon the web before the moisture has permeated the paper and while the latter is of sufficient strength to sustain the strain without wrinkling. The roll M operates to carry the paper extending between it, and the roll I, holds it under tension over the intermediate 120 rollers, and serves the very important purpose of holding the web against and in con-

taet with the surface of roll I, so that the latter will take hold of and carry the web. By applying the traction at two or more points in the length of the web the strain upon the paper is evenly distributed, instead of being concentrated at one point, as would be the case were a single driven roll employed.

We claim—

1. The combination, in a machine for coating a continuous web of paper with sensitized emulsion, of the trough, the immersion-roller projected within the trough with its upper face above the level of the liquid, so that one face only of the paper will be brought in contact with the liquid when drawn around said roller, a series of smooth-faced rolls disposed at intervals around the trough, a hang-up or drying frame, and driving mechanism applied to the last and one or more of the intermediate rollers, substantially as described, whereby the web of paper is drawn through the emulsion and held pressed against the surface of the immersion-roller by the frictional contact of its uncoated face with the smooth surface of the driven roller.
2. In an organized machine for automatically coating a continuous web of paper with sensitized emulsion, the combination of the following instrumentalities: supports for the roll of paper, a trough for containing the sensitized emulsion in a fluid condition, a roller with its lower surface immersed in the trough and around which the paper is conducted to bring one face only in contact with the emulsion, a series of smooth-faced supporting rolls for sustaining the coated web and holding it under tension while the coating is setting, said rollers arranged to make contact with the uncoated

surface of the web and to conduct the latter around the supply-roll and coating devices, driving mechanism for rotating one or more of the series of smooth supporting-rollers to effect the feeding of the web, and a hang-up or driving apparatus upon which the coated paper is delivered and held suspended, substantially as and for the purposes set forth.

3. In an organized machine for making sensitive gelatino-argentic paper for photographic use, the combination of one or more driven smooth-faced rolls for maintaining the coated paper in motion, a suitable hang-up machine, and a coating mechanism consisting of a smooth-faced roll partially submerged in the coating material, said coating-roll being arranged at such a distance from the hang-up machine as to allow the gelatinous coating to set before it reaches the looping-slat, substantially as described.

4. In a machine for coating paper with sensitized gelatinous emulsion, the combination, with the trough and means for heating the emulsion contained therein, of a roller partially immersed in the liquid emulsion around which the paper is drawn, so that one face only will be brought into contact with the emulsion and receive a coating thereof, suitable paper-feeding rolls, and a delivery-roller arranged at such a distance from the trough that the paper is kept continuously in motion until the film has set before delivery to the hang-up frame, as set forth.

GEORGE EASTMAN.
